UNITED STATES PATENT OFFICE.

JAMES JOSEPH GRIFFIN, OF SAN FRANCISCO, CALIFORNIA, AND GORDON MOFFITT PEACOCK, OF SOUTH YARRA, MELBOURNE, VICTORIA, AUSTRALIA.

DOUBLE-SEAMING MACHINE.

1,090,049.

Specification of Letters Patent. Patented Mar. 10, 1914.

Application filed August 24, 1911, Serial No. 645,872. Renewed February 3, 1914. Serial No. 816,334.

To all whom it may concern:

Be it known that we, JAMES JOSEPH GRIFFIN, a citizen of the United States of America, and a resident of the city of San Francisco, in the State of California, United States of America, (whose post-office address is 1131 Shotwell street, in the said city of San Francisco, but who is temporarily residing at 1 Garden street, South 5 Yarra, a suburb of the city of Melbourne, in the county of Bourke, State of Victoria, Commonwealth of Australia,) and GORDON MOFFITT PEACOCK, a subject of the King of Great Britain and Ireland, and a resident of 10 1 Garden street, South Yarra aforesaid, have invented certain new and useful Improvements Relating to Double-Seaming Machines, of which the following is a specification.

20 This invention relates to double seaming machines of the kind having a plurality of seaming heads or stations, such as set forth in our application Serial No. 614,698, filed March 15th, 1911.

25 The objects of the invention are to provide simple, continuous and positive means for feeding the cans from one common source to a multiplicity of seaming devices; and also for removing the seamed cans from 30 said devices in an analogous manner, while always providing for the preservation of the cans from possible injury.

Referring to the accompanying drawings from the several figures of which details 35 and parts have occasionally been omitted or broken away for convenience of illustration:—Figure 1 is a front view of a double seaming machine to which the present invention is applied. Fig. 2 is a plan of Fig. 40 1. Fig. 3 is a plan of the can feeding table. Fig. 4 is a longitudinal section of Fig. 3 on line X. Fig. 5 is a cross section of Fig. 3 on line W. Fig. 6 is an end elevation of Fig. 1. Fig. 7 is a detail sectional view 45 showing the means for placing the cans in position for seaming, and removing them afterward. Fig. 8 is a cross section of the slide. Fig. 9 is a detail view of part of the controlling devices. Fig. 10 is a cross section of Fig. 9. Fig. 11 is an enlarged cross section of the slide modified in structure and operation. Fig. 12 is a side elevation of a moving member of the modified slide. Fig. 13 is a plan of Fig. 12.

The double seaming machine to which the 55 invention is applied is preferably constructed as described in our pending application Serial No. 614,498, and is provided with a number of similar but independently controlled can seaming mechanism 95 arranged 60 in a longitudinal series, and the present invention provides means for feeding cans to each seaming mechanism to be seamed thereby, and for removing the seamed cans.

The invention includes the provision at 65 the front of the machine framework 7 of a horizontal feed table having at its inner side a guide flange 8 having openings 9 opposite each seaming mechanism. At each side of each opening 9, and projecting thereinto may be a plate spring 9^a. Upon the top of the table parallel with the flange 8 is a longitudinal series of guards or guides 10 separated by openings 11. Between the guides 8 and 10 passes a wide feed belt 12. 70 At the outer edge of the table is a guide flange 13, and between the guides 10 and 13 passes a return belt 13^a. The guide 13 is provided near one end of the table with an inwardly curved portion 13^b having beneath 80 it a slot or passageway to accommodate the belt 13^a, and adjoining the portion 13^b is a return opening 11^a. Attached to the guide pieces 8, above the feed belt 12, inner deflecting guides 14 are provided with 85 grooves 15 to accommodate a slide bar 127 hereinafter referred to. Attached to the guides 10, above the feed belt 12, are outer deflecting guides 16. At one end of the table is a guide piece consisting of an inner deflecting portion 17 and an outer deflecting portion 18 attached to the adjacent guides 8 and 10. The feed belt 12 moves in the direction indicated by the arrow Fig. 2, and return belt 13^a moves in the reverse direction; 90 these belts may be driven by any suitable means. As indicated in the drawings the belt 12 is driven by a pulley 12^a on a shaft 12^b driven by belt 12^c from a pulley 12^d on a shaft 31 which drives by means of 100 gears 32 and 57 the shaft 58. The belt 13^a is driven by a pulley 13^a on a shaft 13^b driven by a pulley 13^c and cross belt 13^d from a pulley 13^e on shaft 31. Attached to the inner edge of the table adjacent each of 105 the openings 9 is a can rest or cross 20.

At one end of the main frame is a vertical shaft 58 which is driven by bevel gear-

ing from the longitudinal main shaft as indicated in the drawings. On shaft 58, is a box cam 59 engaged by a roller 61 on the short arm 62 of a bell crank lever which latter is pivoted at 63 on the framework. To the long arm 64 of the bell crank lever is pivoted one end of a link 65 to the other end of which is pivoted a lever 66, attached to a rocking shaft 67. Loosely surrounding said rocking shaft 67 are a series of levers 68 each provided in its boss with a round hole 69. Upon the said rocking shaft are a series of collars 70 each of which adjoins one of the levers 68. Each collar is loose upon the said shaft. In the rocking shaft beneath each collar is a recess 71 in which lies a key 74 pivoted at one end by pivot pin 72, and resting at its other end on a spring 73 in the recess. In each collar 70 is a hole 75 in which is placed a headed pin 76, behind which is a spring 77, the tension of which may be adjusted by a screw 78 tapped into the said hole 75.

A slide consisting of two side members 127 united by a bridge piece 128 is attached by a connecting rod 125 and pivot pin 126 to each of the levers 68. On each side member 127 are a series of pins 129 upon each of which is pivoted an arm 130. Each arm is controlled by a spring 131. The arms on each member 127 that correspond in situation form working pairs. The springs 131^A of the second pair of arms are stronger than their fellows. Each side member is provided with a series of stops 132, one for each arm 130, and each arm has a limiting protuberance 133 adapted to engage with its relative stop 132.

The cycle of operations with this invention is as follows: The cans to be fed are placed upon the feed belt 12 and traveling therewith come into contact either with inner deflecting guides 14 or outer deflecting guides 16, dependent upon the position of the cans upon the belt. If a can contacts with an inner deflecting guide 14 it will be retained thereby and any can which may be immediately following it will pass on and be retained by the next guide 14. Should a can contact with an outer deflecting guide 16 the latter will direct the can toward the inner guides. Should all the inner guides 14 retain cans simultaneously, the other cans then being fed by the belt 12 will simply pass by each inner and outer deflecting guide 14 and 16 successively and be ultimately directed by the end guide 18 onto the return belt 13^A and returned thereby to the guide portion 13^B of guide 13, by which it will be directed through the opening 11^A onto belt 12 to be re-fed. Should a block occur at any of the guides 14 the cans being fed can pass through the openings 11 onto the return belt 13^A. Thus the cans cannot be injured by the feed and the feed is con-

tinuous, and need not be stopped. Each can detained by an inner deflecting guide 14 is prevented from passing freely through its opening 9 by the plate springs 9^A and stops half on and half off the feed belt 12 until its 70 is carried through the opening 9 and poised upon the can rest or cross 20 by the related slide 127. The slide is actuated at the proper time, and its end arms 130, each time the slide recedes, catch and move a can to 75 and over the related cross 20. The can is then raised and presented to the seaming devices as described in our aforesaid application, and after the head or closing disk is seamed to the can body the slide is shifted 80 to remove the can. The slide is properly shifted by the roller 61 following the sinuous groove of the box cam 59 and actuating the bell crank lever which by the link 65 and lever 66 operates the rocking shaft 67 85 and levers 68, each lever 68 being engaged with its relative slide by its respective connecting rod 125. As each slide moves, for example, toward the openings 9 its arms 130 pass the can then upon the cross 20, said 90 arms 130 swinging outwardly to pass the can but resuming their inward positions when past it on account of the springs 131. As the slides recede by the action of the mechanism above mentioned the relative 95 arms 130 coming up behind the can remove it from the cross 20. The slides may deliver the cans to a sheet conveyer (not shown) or any other device for discharging them from the machine. At the time when 100 a can is being removed from a cross 20, the first pair of arms on the slides which have already engaged a can within the relative inner deflecting guide 14, move such can inward, and therefore while one can is being 105 removed from its cross, another is being moved toward the said cross 20. When the latter can is brought over the cross the slide again moves toward the openings 9, the first pair of arms 130 engage a new can, and 110 another pair of arms 130 come into position behind the can on the cross. The first can is then double seamed, and as soon as that operation is completed, the slide moves inward again removing the seamed can and 115 placing another can in position as already explained. The second pair of arms 130, having the stronger springs 131^A, prevent the possibility of a can being inadvertently moved toward its cross by any unforeseen 120 circumstances, such as the pressure of cans being fed moved forward by the belt 12.

In some cases the bridge piece 128 may be dispensed with and the side member 127 nearest the feed end of the machine left stationary, while only the member 127 to which the connecting rod 125 is attached moves (see Figs. 11-13). This member has at its end adjacent the feed table a finger 135 pivoted on a pin 134 having an engagement 130

end 136. Pivoted at 137 to the side of the moving member 127 is a finger operating device 138 having a slot 139 through which passes a guide pin 140 attached to the side 5 of the moving member. At one end of the device 138 is a finger 141 having on its lower side an inclined face 142; and at the other end of the said device 138 is a stop lug 143. Upstanding from the framework 7 adjacent 10 the moving member 127 is a stop 144. When the rising and falling finger are used the plate springs 9^A can be dispensed with and the springs 131^A be of the same strength as their fellows. When using the finger 135 15 only one member 127 is operated, its fellow member remaining stationary. As the member 127 to which the finger is pivoted recedes the protuberance 143 strikes the stop 144 moving the device 138 upon its pivot pin 140. The protuberance 141 then descends 20 upon the finger engagement end 136 below it and elevates the said finger as shown in the drawings (Figs. 11-13). The slide member 127 now advances toward its inner deflecting guide 14 the inclined face 142 engaging the said guide and thereby again 25 moving the device 138. This, however, elevates the protuberance 141 from the finger engagement end 136 permitting the finger 30 135 to fall into a horizontal position by gravity. The finger is now behind the can within the deflecting guide 14 and as the slide again recedes moves the can toward the seaming head. When the protuberance 35 143 and stop 144 again engage, the finger is elevated into a vertical position as already described. The arms 130 during these operations move to allow the cans to pass as formerly. Should any obstruction occur to 40 the slide such as an inadvertent accumulation of cans the said slide upon reaching the same and encountering unnatural opposed pressure is automatically thrown out of gear as long as the obstruction exists there- 45 by preventing a can or cans being injured. It automatically re-commences its operations however when the obstruction is removed. This is effected by the relative pin 76, the point or nose of which is held within the 50 pin hole 69 of the relative lever 68 by the respective spring 77 the tension of which is overcome when an obstruction is met, thereby permitting the pin 76 to recede from the hole 69 and disengaging the lever 68 from the collar 70 which actuates it.

Each collar 70 is actuated by the rocking shaft through the agency of the relative pivoted key 74. The key 74 being pivoted and spring controlled as shown, by depress- 60 ing such key 74 and moving the respective collar 70 along the shaft out of engagement with its relative lever 68, any individual slide may be cut out of operation without interfering with the action of the others.

Having now described our invention, what

we claim as new and desire to secure by Letters Patent is:—

1. In a double seaming machine, a framework carrying a series of seaming heads and having an opening adjoining each head, a traveling can feed belt passing said openings, and stationary guides projecting from said framework over said belt and deflecting cans from said belt to said openings. 70

2. In a double seaming machine, a framework carrying a series of seaming heads and having an opening adjoining each head, a traveling can feed belt passing said openings, guides arranged above said belt and deflecting cans from said belt to said openings, means to prevent the cans moving freely through said openings, and means for positively moving the cans from the openings to the seaming heads. 75 80

3. In a double seaming machine, a framework having a series of openings therein, a can conveyer passing said openings, a series of parallel seaming heads carried by said framework and adjoining said openings at one side thereof and a deflecting guide adjoining each opening at the other side thereof and projecting over the conveyer. 85 90

4. In a double seaming machine, the combination with a seaming head of a reciprocatory slide consisting of a stationary and a moving side member with a series of spring controlled arms pivoted to each member and a rising and falling finger pivoted to the moving member. 95

5. In a can seaming machine, a series of seaming devices, means for continuously feeding unseamed cans along and to one side of said devices, and a reciprocatory slide adjacent each device having pivoted arms for removing seamed cans from the devices and simultaneously moving the unseamed cans from the feed to the said devices. 100 105

6. In a double seaming machine, a framework having inner side pieces with openings therebetween, intermediate side pieces with openings therebetween, a feed belt passing between said inner and intermediate side pieces, an outer side piece adjacent said intermediate side pieces, a return belt passing between said outer and intermediate side pieces, inner deflecting guides attached to the inner side pieces and projecting over the feed belt, outer deflecting guides attached to the intermediate side pieces and projecting over the feed belt; an end deflecting guide extending between said inner and intermediate side pieces above the feed belt, and means for deflecting cans from the return belt to the feed belt. 110 115 120

7. In a can seaming machine, a series of parallel seaming heads a continuously traveling can supply means passing by the seaming heads in the series, and stationary means for deflecting cans from the traveling supply means to each of the seaming heads. 125 130

8. In a can seaming machine, the combination with a series of seaming heads and a traveling can conveyer for feeding cans to each of the heads in the series, of means for deflecting cans from the conveyer to points adjacent the seaming heads in the series, and a reciprocating means for moving each deflected can into the operative sphere of the adjacent seaming head.
- 10 9. In a can seaming machine, a series of seaming heads a single traveling conveyer for supplying cans simultaneously to each of said seaming heads, and stationary guides for deflecting the cans from said conveyer to each of the said seaming heads.
- 15 10. In a can seaming machine, a framework carrying a series of seaming heads and having an opening adjacent each head, a continuously traveling means for conveying cans past the openings, and means adjacent each opening for deflecting cans from the conveyer into the openings; and means for moving the cans from the openings to the heads.
- 20 11. In a double seaming machine, a seaming means, a continuously traveling can conveyer adjacent thereto, an oppositely moving can returning means beside said conveyer, means to deflect cans from said conveyer to said seaming means, and means to direct surplus cans carried past the seaming means from the conveyer to the returning means.
- 25 12. In a double seaming machine, a series of seaming heads, a traveling can feed belt adjacent said heads, and a stationary guide adjacent each seaming head adapted to deflect cans from the feed belt to the related seaming head.
- 30 13. In a double seaming machine, a frame, a series of seaming heads therein, a traveling can feed belt adjacent said series, a return belt adjoining the feed belt, stationary guides adjacent each head for deflecting cans from the feed belt to the related head, and means for directing surplus cans passing all the heads onto the return belt.
- 35 14. In a double seaming machine, a frame having a series of openings, a seaming head adjacent each opening, a feed table, means for moving cans along the table and past the several openings, an inner deflecting guide on the table adjacent each opening, and outer deflecting guides alternating with the inner deflecting guides adapted to direct cans to the inner guides.
- 40 15. In a double seaming machine, a frame having a series of openings, a seaming head adjacent each opening, a feed table, means for moving cans along the table and past the successive openings, an inner deflecting guide on the table adjacent each opening adapted to direct cans thereto, and outer deflecting guides alternating with the inner
- deflecting guides; and adapted to direct cans to the inner guides, with a return belt passing the openings between said outer guides.
- 45 16. In a double seaming machine, a frame having a series of openings, a seaming head adjacent each opening, a can feed belt passing said series of openings, an inner deflecting guide adjoining each opening, and outer deflecting guides alternating with the inner guides and adapted to direct cans thereto, and a return belt passing the openings between said outer guides.
- 50 17. In a double seaming machine, the combination of a series of seaming means; and means for feeding cans alongside the series of seaming means; with a can selecting means for each seaming means operated by a common means and controlling means therefor whereby cans are automatically taken from the feeding means to each individual seaming means; each such can selecting means being unaffected by the operating or stoppage of any other can selecting means.
- 55 18. In a double seaming machine, the combination of a series of seaming means, and means for feeding cans past said series of seaming means; and independently operated can selecting means by which cans are automatically taken from the feeding means to each individual seaming means; each can selecting means being unaffected by the operation or stoppage of the other can selecting means; with means for automatically returning cans to be re-fed should any blockage occur, or should they not be taken to a seaming means when first fed.
- 60 19. In a can seaming machine, the combination with seaming heads, and means for feeding cans alongside the said heads; with a reciprocating slide adjacent each seaming head having opposite pivoted arms adapted to simultaneously engage and move a can from the feed to the said head when the slide moves in one direction, and means for yieldingly controlling said arms.
- 65 20. In a can seaming machine, a plurality of seaming heads, and means for continuously feeding unseamed cans alongside said heads; with a reciprocating slide adjacent each head movable at right angles to the feeding means and having a plurality of spring controlled pivoted arms adapted to remove a seamed can from the head and simultaneously engage and move an unseamed can from the feed to the head.
- 70 21. In a can seaming machine, the combination of a plurality of seaming heads, and means for feeding cans alongside said heads; with a reciprocating slide adjacent each head, two series of opposite pivoted arms mounted on opposite sides of each slide and adapted to move one can from the feed to the head for seaming and simultaneously
- 75 80 85 90 95 100 105 110 115 120 125 130

moving another can out of such position as the slide reciprocates, and means for independently operating said slides.

22. In a can seaming machine, the combination with a plurality of seaming heads, and means for feeding cans alongside said heads; with a reciprocatory slide adjacent each head consisting of two side members adapted to pass on opposite sides of a can, and a series of spring controlled arms pivoted to each member, said slide being adapted to move one can from the feed to the head and simultaneously remove another can out of seaming position as the slide reciprocates, and means for independently operating said slides.

23. In a can seaming machine, the combination with seaming heads, and means for

feeding cans beside the said heads; with a reciprocatory slide adjacent each seaming head having opposite pivoted arms adapted to simultaneously engage and move a can from the feed to the said head when the slide moves in one direction, and means for yieldingly controlling said arms; with means by which each slide is automatically operated without being affected by the operation or stoppage of the other similar slides.

In testimony whereof we affix our signatures in presence of two witnesses.
